UNITED STATES PATENT OFFICE.

GEORGE I. GALITZKA, OF NEW YORK, N. Y.

TELEPHONE APPARATUS.

1,256,123.

Specification of Letters Patent. Patented Feb. 12, 1918.

Application filed March 14, 1917. Serial No. 154,670.

To all whom it may concern:

Be it known that I, GEORGE I. GALITZKA, a citizen of the United States, and a resident of New York, borough of Manhattan, 5 in the county of New York and State of New York, have made and invented certain new and useful Improvements in Telephone Apparatus, of which the following is a specification.

10. My invention relates to telephone apparatus, and particularly to one which is adapted to notify and warn the subscriber that the local switchboard operator's set is connected in the line and the local operator 15 therefore capable of listening in.

A serious objection to the ordinary form 20 of telephone system is installed in apartment houses, and other places where a local switchboard is maintained, is the listening-in of the operator. In a great many instances, this objection to the use of the economical local switchboard, and its associated 25 circuits, has caused the subscribers to install private wires, even though the latter entails a considerably higher rate of telephone rental. Accordingly, an object of my invention is to provide a telephone apparatus including a local switchboard, wherein the 30 listening-in of the local switchboard operator is reduced to a minimum, if not entirely prevented, by producing a warning signal in the subscriber's set that the operator's talking and listening set is connected in line, and reminding the local operator 35 that the subscribers are aware of her listening-in.

In accomplishing the aforementioned ends I have provided an apparatus in which one 40 of the metallic wires of the subscriber's line is utilized, so that the expense incident to the installation of my apparatus is reduced to a minimum. Other objects and advantages will appear as the description proceeds, wherein it is to be understood that 45 changes in the precise embodiment of the invention can be made within the scope of what is claimed without departing from the spirit thereof.

The preferred embodiment of my inven-

tion is disclosed in the accompanying drawings, wherein:

Figure 1 is a diagrammatic view of a telephone system embodying the characteristic features of my invention;

Fig. 2 is a diagrammatic view of the circuits involved, arranged to produce the warning signal aforementioned, wherein the circuit for producing the warning signal is isolated and in no way electrically connected to the telephonic circuits.

Referring specifically to Fig. 1, the telephone sets A, B, C, D and E, represent the ordinary subscribers' phone sets, and are directly connected to a local switchboard F. The subscribers' line circuits 10 lead to the 65 respective jacks 11 in the local switchboard, and are connected to the service wires W, or to one another, by the plugs 12, and their respective cord circuits 13.

The local switchboard operator's listening-in keys 14, which connect the operator's talking and listening set (not shown) to the cord circuits, are provided with the metallic projections 15, electrically isolated from the main portions of the listening-in 75 keys by the insulators 16.

In order that a signal will be produced at the particular subscriber's phone set who is using the phone, that the local switchboard operator has connected her listening 80 and talking set into the line, an indicator 17, preferably in the form of an electric lamp, is provided in each of the subscriber's sets A, B, C, etc. The electric indicators, preferably in the form of electric lamps, are 85 electrically connected to one of the metallic wires 18, which go to make up the subscriber's line circuits 10. The remote sides of the electric indicators 17 are electrically connected to a common return wire 19, 90 which, in turn, is electrically connected to one side of the switches which are formed by the moving elements 15 attached to the listening-in keys, and the contact points 20. The common return wire 19 from the electrical indicators, is connected in parallel to one of the contact points 20 of each of the 95 said switches. The other of the contact

points are connected in parallel by the wire 21, to a source of electrical energy 22. The source of electrical energy is also connected, and in parallel, by the wires 23, to one wire 5 of the cord circuits 13, which will, when the plugs 12 are inserted in the jacks 11, be electrically connected to the wires 18 of the subscriber's lines.

With the circuits so arranged, and with 10 one of the plugs 12 inserted in one of the jacks 11, the indicator in the subscriber's set which has been connected in circuit by the plug will be connected to one side of the source of electrical energy 22. Should the 15 operator now depress the listening-in key, the circuit from the source of electrical energy to the said subscriber's indicator, will be completed and the indicator will be energized and a warning signal produced. In 20 this connection, it will be apparent that the indicator, although preferably partaking of the nature of an electric lamp, may be of any desired nature, capable of producing a warning signal when electrically energized, 25 such as a drop enunciator, a bell, etc. An indicator 24 is installed in the local switchboard F, and is connected to the return wire 19 and to one of the contact points 20 of the listening-in key supplemental switches 30 so that this indicator will be flashed when the operator's listening-in key is depressed, and the local switchboard operator will thereby be reminded that the subscribers are 35 aware of her listening-in.

The somewhat modified arrangement illustrated in Fig. 2 is similar to the foregoing, with the exception that the plug 25 and jack 26 are provided with the electrical connectors 27 and 28, which are independently connected to the signal circuit 29, the latter including a source of electrical energy 30, the supplemental switch 31 (which is mounted upon the operator's listening-in key), and the indicator or lamp signal 32. By so 40 modifying the plug and jack, the signaling circuit 29 is electrically isolated, and independent of the telephone circuit 33. I do not wish to limit my invention to the exact arrangement of circuits, and the construction of the indicators and apparatus as 45 shown, as it will be readily apparent to those skilled in the art that changes and modifications may be made therein and still attain and accomplish the aforementioned ends, 50 and such changes and modifications fall clearly within the scope of my invention.

What I claim is:—

1. The method of preventing the listening-in of the operator of a local switchboard, consisting in providing a signaling apparatus connected with the listening-in key of the local switchboard and producing a visible warning signal at the subscriber's set 60

upon the actuation of the said listening-in key.

2. An apparatus of the class described, 65 consisting of a visible indicator at the subscriber's set, a switch adapted to be actuated when the operator's talking and listening set is connected in line, and an electric circuit including a source of energy connected to said visible indicator and said switch, said indicator adapted to produce a visible warning signal when the operator's talking and listening set is connected in line. 70

3. An apparatus of the class described, 75 consisting of a visible indicator at the subscriber's set, a switch adapted to be actuated when the operator's talking and listening set is connected in line, an electric circuit including a source of energy connected to said visible indicator and said switch, said indicator adapted to produce a visible warning signal when the operator's talking and listening set is connected in line, and a visible indicator at the local switchboard connected in the aforementioned circuit and adapted to produce a visible warning signal similar to the warning signal of the indicator of the subscriber's set. 80

4. An apparatus of the class described, 85 consisting of a local switchboard including plugs, jacks, and listening-in keys, and subscribers' telephone sets, of indicators associated with the subscribers' telephone sets, and means whereby the indicator of the subscriber whose phone set is in use produces a visible signal when a listening-in key of the local operator's set is actuated. 90

5. A telephone apparatus including a local 100 operator's circuit and a subscriber's line circuit, a listening-in switch whereby the two are electrically connected, a second switch mechanically connected to and operated by said first switch, and means electrically connected to said second-mentioned switch 105 adapted to produce a visible warning signal at the subscriber's set when the first-mentioned switch is closed.

6. In a telephone apparatus the combination 110 of a local operator's switchboard including listening-in keys for connecting the local operator's circuit with the subscriber's line circuit, of a switch mechanically connected to said listening-in key switch and operated thereby, and means electrically connected to said second-mentioned switch 115 adapted to produce a visible warning signal at the subscriber's set when the said listening-in key is operated and the local operator's circuit connected to the subscriber's line circuit. 120

7. In an apparatus of the class described the combination with a local operator's switchboard including a listening-in key 125 switch, a subscriber's line circuit and local

operator's circuit, of a switch mechanically connected to and operated by said listening-in key switch, an electric lamp located at the subscriber's telephone set electrically connected to said second-mentioned switch and adapted to be energized and lighted when said listening-in key switch is operated and the local operator's circuit connected to the subscriber's line circuit.

Signed at New York, borough of Manhattan, in the county of New York and State of New York, this 13th day of March, A. D. 1917.

GEORGE I. GALITZKA.
